UNITED STATES PATENT OFFICE.

VICTOR HENRI, ANDRÉ HELBRONNER, AND MAX VON RECKLINGHAUSEN, OF PARIS, FRANCE, ASSIGNEES, BY MESNE ASSIGNMENTS, TO THE R. U. V. COMPANY, INC., A CORPORATION OF NEW YORK.

APPARATUS FOR STERILIZING LIQUIDS BY MEANS OF ULTRA-VIOLET RAYS.

1,091,221.

Specification of Letters Patent. Patented Mar. 24, 1914.

Application filed June 7, 1910. Serial No. 565,612.

To all whom it may concern:

Be it known that we, VICTOR HENRI and ANDRÉ HELBRONNER, citizens of the Republic of France, and MAX VON RECKLINGHAUSEN, a subject of the Emperor of Germany, residing at Paris, France, have invented new and useful Improvements in Apparatus for Sterilizing Liquids by Means of Ultra-Violet Rays, of which the following is a specification.

This invention relates to sterilization of water and other liquids, and has for its object to provide an improved apparatus by means of which the well-known bactericidal effect of ultra-violet rays may be advantageously utilized for the liquids which are permeable to these radiations.

The means which we employ comprises an electric lamp which in operation emits ultra-violet rays, for instance a mercury vapor lamp having a quartz or silica container is very suitable for the purpose. Such a lamp if immersed in the water to be sterilized would, however, not work with a satisfactory yield or efficiency by reason of the cooling effect of the water. We therefore according to our invention provide an additional envelop of quartz or silica, either surrounding the entire lamp or surrounding only that portion of it which emits the ultra-violet rays. The space between the lamp container and the outer envelop is exhausted up to a very high vacuum so that the radiation of heat to the surrounding water is thoroughly prevented and thus the normal working of the lamp is not affected.

We have suggested a mercury vapor lamp as being suitable for the purpose of our invention. It will be understood, however, that there are other electric lamps or other systems for emitting ultra-violet rays for which the present arrangement can be usefully adopted. In the case of the mercury lamp the intermediate vacuum space allows the lamp to work with the least expenditure of energy so that the cost of sterilization may be reduced to the lowest possible.

Our improved apparatus is illustrated in the accompanying drawings, in which—

50 Figure 1 is a sectional view showing one

method of carrying out the invention and Fig. 2 is a similar view showing a modification.

Referring to Fig. 1, the tank 1 holds the liquid to be sterilized: 2 indicates a mercury vapor lamp of any suitable kind, provided with a container 3 of quartz or silica and having leading-in wires 4 and 5. The entire lamp is inclosed in an envelop 6 of quartz or silica, and the space 7 between the envelop and the lamp is exhausted to such a degree of vacuum that the gas remaining therein will not prevent the passage of ultra-violet rays.

In Fig. 2 the outer envelop of the lamp 6 marked 8 surrounds only that portion 9 of the lamp which emits the ultra-violet rays as those parts 10 containing the mercury pools act as cooling chambers when the lamp is in operation, and consequently may be immersed directly in the surrounding liquid.

Our improved apparatus may be used with other liquids besides water which it is desired to sterilize or in which it is desired to stop the process of fermentation.

What we claim is:

1. Apparatus for sterilizing liquids, comprising the combination of a tank for containing the liquid to be sterilized, a lamp adapted to emit ultra-violet rays immersed 80 in said liquid, and an envelop surrounding said lamp, the intermediate space being exhausted of air.

2. Apparatus for sterilizing liquids, comprising the combination of a tank for containing the liquid to be sterilized, a vapor electric lamp having a container permeable to ultra-violet rays immersed in said liquid, and an envelop permeable to ultra violet rays surrounding said lamp, the space between the lamp and the envelop being exhausted of air.

3. Apparatus for sterilizing liquids comprising the combination of a tank for containing the liquid to be sterilized, a vapor 95 electric lamp immersed in said liquid, and an envelop permeable to ultra-violet rays surrounding the part of the lamp adapted to emit ultra-violet rays, the intermediate space being exhausted of air.

4. Apparatus for sterilizing liquids comprising the combination of a tank for containing the liquid to be sterilized, a mercury vapor lamp having a quartz container immersed in said liquid, and a quartz envelop surrounding said lamp, the space between the lamp and the envelop being exhausted of air.

In testimony whereof we have hereunto

subscribed our names this 25th day of May 10
1910.

VICTOR HENRI.

ANDRÉ HELBRONNER.

MAX VON RECKLINGHAUSEN.
